AERIAL DELIVERY CONTAINER

William L. Lindsey and Harry Wilson,
Fort Benning, Ga.

Application April 13, 1942, Serial No. 438,745

1 Claim. (Cl. 217—5)

(Granted under the act of March 3, 1883, as
amended April 30, 1928; 370 O. G. 757)

The invention described herein may be manufactured and used by or for Government for governmental purposes, without the payment to us of any royalty thereon.

This invention relates to parachute apparatus and is more especially concerned with a container for holding weapons, ammunition or other articles for dropping by parachute from an aircraft.

An object of the invention is to provide a container which is light in weight yet strong and durable and able to withstand the severe shocks incident to its use.

Another object is to so construct and arrange the device that it may be opened in a minimum of time after landing.

Other objects and meritorious features of design will be more fully recognized by a consideration of the following description and a reference to the accompanying drawings, wherein,

Fig. 1 is a view of the container as it appears when closed.

Fig. 2 shows the container with one door open.

Fig. 3 shows the container with both doors open.

Fig. 4 is a transverse section taken at 4—4 of Fig. 1 showing the construction of the bottom member.

Fig. 5 is a transverse section taken at 5—5 of Fig. 3 showing the door construction.

Like reference characters refer to like parts throughout the drawings.

The container, when closed as in Fig. 1, is in the form of a hollow hexagonal prism and comprises a top member 10, a bottom member 12, a front 14, a back 16, and two side doors 18 and 20.

The bottom member 12 comprises a relatively thick hexagonal board 30 which is reinforced by a series of six battens 24 secured to the board at its periphery. At each juncture of two adjoining battens, a notch 26 is cut from the outside inward, but not clear through, to provide pockets for the lower ends of the four vertically extending reinforcing bars 28, and the two vertically extending reinforcing bars 28a. The bars 28 and 28a are exactly alike but are given different reference characters to facilitate description. The arrangement of the battens 24 on the board 30 provide a well 31 into which a hexagonal piece of thick felt (not shown) may be laid to provide a shock absorber for the contents when the container alights.

The top member 10 is made up of a hexagonal board which is in most respects like the bottom board 30 except that it may be slightly thinner,

It is also reinforced by a series of six battens 24 with notches 26 cut at their junctures for the upper ends of the reinforcing bars 28 and 28a.

Each reinforcing bar 28 or 28a is made up of two bars with the edges beveled where they join, to form a shallow trough, the cross section of one of the bars being such that the ends of the bars fit into the notches 26. Four of the bars 28 are permanently secured in their notches 26 while the other two bars 28a are secured to the inside of the doors 18 and 20 and hold the two panels 32 of a door together, the ends of the bars 28a swinging into their notches 26 when the doors are swung to closed position.

15 The front 14 and back 16 each comprise a single panel 32 fastened at their top and bottom ends to the members 10 and 12 respectively, and at their edges to the bars 28. The doors 18 and 20 are hung on hinges 34 which join the doors 20 to the back 16. Two hasps 36 and 38 are hinged respectively to the swinging edges of the doors 18 and 20, their free ends being slotted to slip over the staple 40 which is anchored in the front 14. A spring snap 41 is inserted in the staple 40 25 over the hasps.

25 Wide sheet metal reinforcing bands 42 and 44 surround the top member 10 and bottom member 12 respectively, the bands being of less width than the thickness of the members and battens 30 together, whereby the panels 32 which compose the doors 18 are provided an abutment against which to close. The bands are cut away where they cross the notches 26 into which the ends of the bars 28a must swing when the doors are closed. Vertical sheet metal strips 46 are provided at the edges of the front 14 and back 16, and at the edges of the two doors 18 and 20. A single length of strap iron 48 is brought across the bottom 12 and up over the front 14 and back 40 16 to the top 10 where it is fastened to the band 42, a loop being formed at each end for holding the D rings 50 to which the risers of a parachute are secured.

45 After the container lands, it may conveniently be opened when in an upright position by undoing the spring snap 41, grasping the hasps 36 and 38, and throwing back the doors 18 and 20, whereupon the weapons or other contents may be removed.

Having described our invention, we claim,

50 A quick opening aerial delivery container which comprises top and bottom members each consisting of a polygonal board with a series of battens arranged along its periphery and secured thereto, with sheet metal reinforcing bands sur-

rounding them, said battens having notches along the outer edges at the interfacing ends, a series of reinforcing bars each made in the form of a shallow trough, the top and bottom ends of said bars being fitted into said notches, a series of panels peripherally covering the top and bottom members and the space between them, to form a hollow polygonal prism, opposite front and back panels being secured at the ends to the top and bottom members and at the sides to pairs of said reinforcing bars, said pairs being fastened in said notches and to said top and bottom members, the remaining panels being secured together at their interfacing edges by securing

them to the remaining reinforcing bars to form doors, said remaining reinforcing bars being left unfastened in their respective notches and said sheet metal bands being cut away to allow the 5 reinforcing bars to swing into their notches, hinges connecting one edge of each door to the back panel, a hasp on the other edge of each door adjacent the edges of the front panel, a single staple on the front panel for receiving both 10 hasps, and a spring snap removably extending through said staple above said hasps.

WILLIAM L. LINDSEY.
HARRY WILSON.
